UNITED STATES PATENT OFFICE.

ROBERT MAGRANE, OF NEW YORK, N. Y., ASSIGNOR TO ANCHOR CAP & CLOSURE CORPORATION, OF BROOKLYN, NEW YORK, A CORPORATION OF NEW YORK.

SEALING-MACHINE.

1,332,737.

Specification of Letters Patent.

Patented Mar. 2, 1920.

Original application filed February 26, 1914, Serial No. 821,239. Patent No. 1,134,070, dated March 30, 1915.
Divided and this application filed February 25, 1915. Serial No. 10,525.

To all whom it may concern:

Be it known that I, ROBERT MAGRANE, a citizen of the United States, residing at New York, in the borough of Queens and State of 5 New York, have invented new and useful Improvements in Sealing-Machines, of which the following is a specification.

This invention relates to sealing mechanism or capping machines and has particular references to dies and their operation. 10 The present application is a divisional application divided from a co-pending application filed February 26, 1914, Serial No. 821,239, issued March 30, 1915, as Patent 15 No. 1,134,070, and certain features herein disclosed but not claimed are claimed in a co-pending application Serial Number 871,732 filed November 12, 1914.

One object of the present invention is to 20 simplify the sealing die construction and operation; another object is to provide a machine that will seal a metallic closure to a glass receptacle without danger of breaking the latter, and still other objects will appear 25 in the following description and claims.

Referring to the drawings:

Figure 1 is a side elevation of a part of the mechanism showing a sealing chamber and valve;

30 Fig. 2 is a plan showing the valve timing mechanism;

Fig. 3 is a side elevation in section taken on the line 3—3 of Fig. 2;

35 Fig. 4 is a sectional elevation of the power cylinder and a vacuum chamber taken on the line 4—4 of Fig. 2;

Figs. 5 and 6 are elevations, partly in section, of the mechanism for closing the 40 vacuum chambers; and

Fig. 7 is a detail showing the manner of locking the sealing chamber.

While the machine disclosed is adapted to seal containers in a vacuum, those features of the apparatus do not form part of 45 the present invention but are claimed in the co-pending application referred to.

In Figs. 1 and 4, a vacuum chamber is shown as formed by a cup-shaped cylinder 10 which is closed at the bottom by a plug 50 cap 11 and is carried within a circular flange 12 forming a part of the table bed 13. The cylinder 10 is equipped with a shoulder 14 and a threaded portion 15 by which, to-

gether with the collar 16 and nut 17, it is attached to the table bed. Within the cylinder 10 is a second cylinder 18 of a similar form, but movable in a vertical direction and somewhat resembling a trunk piston. A cap 19 fits over the open upper ends of both cylinders and forms the closure for the 60 vacuum chamber. This cap is removable; the receptacle to be exhausted of air and then sealed is dropped into the open cylinder where it occupies the position indicated by the dotted lines α , α , whereupon the 65 cap is replaced. The chambers have their respective closures applied simultaneously and by the same common mechanism although the closures may be operated successively if desired.

70 As shown in Figs. 2 and 4, the caps or closures 19, 19 are both attached to the ends of a thin somewhat elastic beam 25 which is pivoted at its center in a manner to be described. The movement of the caps and the 75 beam in opening the chambers is first vertically upward until the closures are clear of the chambers, and then the caps rotate with the beam 25 in a clockwise direction for a distance of 90 degrees, the caps and 80 the beam then being in the position indicated at 25 a and 19 a in Fig. 2. The closing movement takes place in reverse order.

The construction producing this movement is best shown in Figs. 3, 5 and 6. As 85 shown, the beam 25 is carried by a head 26 which is pinned to a tubular shaft 27. The shaft 27 has both a vertical and a rotary motion within a bearing sleeve 28 clamped to the table bed 13 by a nipple 29. Two diagonal cam slots 30, 30 diametrically opposite each other are formed in the shaft 27, and also two straight longitudinal slots 31, 31 are formed at its lower end. The shaft 27 is further provided with two shoulder tracks 32, 32, two extensions 33, 33 and a clamp 34 for the extensions. The nipple 29 carries at its lower end a guide sleeve 35 which is equipped with two longitudinal parallel slots 36, 36, and at its lower end is fitted with two rollers 37, 37 located opposite each other.

90 As shown in Fig. 3, a pedal 38 is fulcrumed at 39 to the frame 40 and is adapted to move the rod 41 downward against the tension of springs 42, 42 when it comes 95 into contact with the collar 43 carried by

the rod. An auxiliary spring 44 tends to hold the pedal upward.

The upper end of rod 41 enters the tubular shaft 27 and is equipped with a head 45 which carries a fixed shaft 46 upon which are mounted two pairs of rollers 47, 47 and 48, 48. The rollers 47, 47 engage the diagonal slots 30, 30 while the rollers 48, 48 engage the slots 36, 36.

- 10 When the chambers are open, and the closures are in the broken line position shown in Fig. 2, the springs 42, 42 maintain the rod 41 and its head 45 in their uppermost position, in which position the rollers 47, 47, 48, 48 are in the upper parts of their respective slots 30 and 36. In this position the shoulder tracks 32 at the lower end of the tubular shaft 27 rest upon the rollers 37.
- 20 The chambers are closed by depressing the pedal 38 which carries the rod 41 downward as described. The rod and the head 45 cannot rotate as the rollers 48, 48 attached thereto travel in the vertical slot 25 guides 36, 36. The initial movement of the head 45 downward however operates upon the diagonal slots 30, 30 in the tubular shaft 27 and rotates the shaft 27, beam 25 and closures 19 in an anti-clockwise direction 90 degrees, in which position the closures are directly over the chambers. The shaft 27 and closures carried thereby are prevented from downward movement during this rotation by the shoulder tracks 32, 32, which 35 are at this time riding on the rollers 37, 37 which support shaft 27 during this part of its movement. When the shaft has rotated 90 degrees the rollers 47, 47 have reached the bottoms of slots 30, 30; and the shoulder tracks 32 have run off their supporting rollers 37, 37 so that the further movement of the head 45 carries downward with it the shaft 27 and the closures carried thereby. During this downward movement of 45 the shaft and closures any rotation is prevented as the straight open slots 31, 31 in the lower part of the shaft are engaged by the rollers 37, so that the closures move directly downward upon their respective 50 chambers.

It will be seen that a single depression of the pedal will cause the closures first to swing through an arc of 90 degrees to a position directly over the chambers and then 55 to move directly downward to seal the chambers, and also when the closures are permitted to move upward, they will move directly upward until they clear the chambers and then swing backward 90 degrees 60 to the first position.

The particular method of sealing the receptacle that is indicated at x , x in Fig. 4 is by applying a metallic cap indicated at y in the same figure equipped with an annular beading inclosing a gasket and by

squeezing the gasket against the container to form the seal. A sealing cap of this type and a machine for applying the cap is disclosed in Patent No. 874,201 issued to J. V. Hull, December 17, 1907, to which 70 reference may be made. As indicated in Fig. 4, the cap y is provided with the metallic beading z within which the gasket to be squeezed is located. To effect the squeezing, pressure is brought to bear upon 75 the beading vertically, as described in the patent referred to, by annular jaws located above and below the beading. In machines of the prior art in which such sealing is effected, the lower jaw has necessarily been 80 made sectional, as the receptacle and cap have been inserted in the chamber either through the side or bottom of the chamber, so that the beading has to clear the lower jaw both before and after sealing. 85

This sectional and costly construction of the lower jaw is eliminated in the present machine by providing the described chamber and its cap-like closure. This improved construction permits the lower jaw to be 90 formed simply of a hardened steel annular member, shown at 50 in Fig. 4, which is carried upon an inner shoulder of the piston 18. A coacting annular jaw formed likewise of a single piece of turned steel is 95 mounted upon the underside of the cap 19, as shown at 51 in the same figure. A further advantage of this construction is that it permits the easy change of jaw rings so that the machine may handle different sizes 100 of sealing caps, whereas in former types of machines the substitution of an entire sealing chuck is necessary when the size of the caps is to be changed.

This method of mounting the sealing jaws 105 requires the locking of the closure cap 19 to the chamber 10 so that the cap will withstand the thrust of the sealing pressure. For this purpose any suitable locking means may be employed. That shown in the present instance, in Figs. 2, 4 and 7, is fully described in the Patent No. 1,134,070 referred to above.

As best shown in Fig. 4, the support for the lower ring die is chambered so as to 115 allow the insertion of the receptacle within the support and within the lower die 50. The upper ring die 51 is supported by a disk 19 which reduces to a minimum the dead space above the receptacle and closure, this being of great advantage in sealing with a vacuum.

Power for operating the sealing mechanism may be derived from various sources, and the mechanism may be variously constructed. In the present machine, the force of atmospheric pressure operating against a vacuum is utilized to produce the power to operate the sealing mechanism; but these features form no part of the present in- 125 130

vention, and are fully described in the co-pending application referred to.

I claim:

1. In a sealing device for receptacles adapted to compress an annular beading on a closure to form a side seal against a substantially incompressible side wall of the container, said device comprising an integral sealing die ring through which the receptacle is adapted to extend and upon which the bead of the closure is adapted to rest, an upper co-acting die adapted to engage the upper portion of said bead, and means to move said dies relatively under sufficient pressure to flatten the bead and compress the same to squeeze a suitable gasket between the bead and the side wall of the container to effect the side seal.
2. In a sealing device the combination of an integral annular die member adapted to encircle the container to be sealed, said annular die member having a sealing face adapted to engage the closure to be operated upon, an upper die member arranged for co-operation with said annular die member, said upper die member having a sealing face adapted to co-act with the sealing face of the annular die member to deform the closure independently of the container and means for effecting relative movement of said die members to permit insertion of a container

intermediate them and within the annular die member.

3. In a device for sealing closures to containers in combination a pair of co-acting annular die members each of integral structure, said die members being provided with opposing sealing faces adapted to engage a closure positioned between them, means for effecting separation of said die members to permit the insertion and removal of a container through one thereof, and means for effecting relative movement of said die members to deform the closure independently of the container.

4. In a device for sealing closures to containers, in combination, an integral die member provided with an aperture for the reception of a container, said die member being provided with a continuous sealing face extending about the aperture, a second die member disposed to coöperate with said integral die member to engage a closure, and means for effecting relative movement of said die members to permit the insertion of a container in the aperture of the integral member, and to compress a closure thereon.

ROBERT MAGRANE.
